(57) **CLAIM**

The ornamental design for a charging case for earphone as shown and described.

DESCRIPTION

FIG. 1 is a perspective view of front, top and left side of a charging case for earphone showing our new design; FIG. 2 is a perspective view of front, top and right side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view with the lid open thereof.

The broken lines depict portions of the charging case for earphone that form no part of the claimed design.

1 Claim, 8 Drawing Sheets
